UNITED STATES PATENT OFFICE

HARRY COHEN, OF WASHINGTON, DISTRICT OF COLUMBIA

PENCIL SHARPENER

Application filed October 11, 1921. Serial No. 507,032.

My invention relates to pencil sharpeners and has for one of its objects to provide a pencil sharpener which is simple, effective and automatic in operation.

5 A further object is to provide a pencil sharpener which is set into operation by pressure exerted on the pencil.

Other objects will be apparent from an inspection of the following description and the 10 accompanying drawing in which:

Fig. 1 is a vertical section of the pencil sharpener, parts being shown in elevation.

Fig. 2 is a section on the line 2—2 of Fig. 1.

15 Fig. 3 is a vertical section of the pencil sharpener showing a modification.

Fig. 4 is a section on the line 4—4 of Fig. 1.

Fig. 5 is a section on the line 5—5 of Fig. 1.

Fig. 6 is a detail part sectional view of the gear track and associated cutter.

20 Fig. 7 is a detail view, partly in section, of the spring returning means; and

Fig. 8 is a bottom plan view of the cutter ring.

Referring to the drawings, the numeral 1 25 designates an outer frame or casing provided with a helical groove 2 of suitable pitch. Mounted within the frame 1 is a vertically and rotatably movable member 3 provided with the helical rib 4 cooperating with the 30 helical groove 2 in the casing 1. Resting on the ledge 5 in the upper end of the member 3 is an annular gear track member 6 having integral therewith the gear track 7 and provided with the central opening 8. The gear 35 track member 6 has a raised portion 9 provided on its under side with an annular channel 10 for a purpose to be described later. Depending from the top of the outer casing 1, which top may be integral with the body 40 portion of the casing or detachably fixed thereto, are a plurality of lugs 11 extending into the hollow cylindrical members 12 which depend from the gear track member 6. As shown by the drawings, the lugs 11 are integral 45 with the top of the casing 1 but it is obvious that they may be separable therefrom and detachably connected thereto. It is equally obvious that the cylinders 12 may be cast integral with the member 6 or they may 50 be detachably connected thereto. Mounted at

the bottom of the cylindrical members 12 is a gear support 13 in which are journaled the spindles 14, 15 and 16 of the spur gears 17, 18 and 19 so that these spindles may freely rotate in said support 13.

55 The member 3 is provided at its bottom with an annular internal gear 20 which meshes with the gears 18 and 19. The upper end of the spindle 14 has a squared portion 21 fitting into a recess in the carrier 22 so that when gears 18 and 19 rotate the gear 17, the carrier 22 is also rotated. Mounted in the carrier 22 are the milling cutters 23 of a well known type with their axes disposed at an angle to the plane of rotation of the carrier 22. The cutters 23 are, of course, rotatably journaled in the carrier 22 so that as the cutters are carried around by the carrier 22 they may also rotate in the said carrier. The cutters 23 have bevel gears 24 meshing 60 with the gear track 7 which is held from rotation by the lugs 11, as will hereinafter be described. Secured to the spindles of the cutter 23 above their bevel gears is a ring 25 which fits into the channel 10 of the gear track 65 member 6, the function of the said ring being to hold said cutters in the proper position as they are revolved by the carrier 22. This retaining ring 25 has two circular recesses 25^a in which fit rotatably therein in an obvious 70 manner the spindles 23^a of the cutters 23, as shown in detail by Fig. 6.

75 As hereinbefore stated, the geartrack member 6 is held from rotation by the lugs 11 and since the support 13 is fixed relative to the member 6, it is apparent that the support 13 will likewise be held from rotation. Thus, it is readily seen that as the member 3 is moved longitudinally it will rotate because of the cooperation of the helical ribs 4 with the helical groove 2 in the stationary casing 1, and as the member 3 rotates, its annular gear 20 meshes with the gears 18 and 19 imparting rotation thereto which in turn mesh with the smaller gear 17 and thereby rotate said gear 85 and the carrier 22. As the carrier 22 rotates, the milling cutters 23 revolve about a central axis and by reason of the meshing of the bevel gears with the gear track 7, the said cutters 90 are caused to independently rotate in the car- 100

rier 22. These cutters 23 may be aptly described as planetary cutters.

It should be noted that the mechanism within the casing 1, comprising the ribbed member 3, the gear track member 6, the gear support 13, the gears, the carrier 22 and the cutters 23, moves longitudinally as a unit and at the same time the various parts revolve and rotate as required in order to produce an operative structure. The longitudinal movement of the members is resiliently restrained by the helical springs 26, one end of each spring being fixed to the lug 11 and the other end to the cylindrical members 12, so that when the force that moves the mechanism is removed the springs will return the mechanism to its normal position near the top of the casing 1. In order to maintain the gear track member 6 in place on the ledge 5, there are provided a plurality of fingers 27 which are secured to the top of the member 3 by screws or other suitable means and which overlap the member 6 holding it to the ledge 5 as required.

Fixed in the central opening 8 of the member 6 is a spring 29 of the form shown, disposed beneath opening 30, and as pressure is brought to bear on the pencil inserted through the opening 30 and opening 8, the pencil first coming into contact with the spring 29 depresses the member 3, thus rotating it and the cutters before the pencil comes into contact with the cutters and so the mechanism has an opportunity to start into operation before the pencil can oppose, by any chance, its operation. Subsequently the pencil is pushed through the opening in the spring into engagement with the cutters which are by that time revolving and rotating and thus the pencil is sharpened. The use of the spring 29, while desirable, is not absolutely necessary as the push on the pencil imparted to the cutters will cause the necessary movement of the parts to cause the sharpening of the pencil. To prevent the breaking of the point of the pencil as the pencil is pushed into contact with the cutters to secure the desired point length, there is provided in the carrier 22 a depression 31 to accommodate the pencil point. The shavings are caught in the removable pan 32 which may be emptied as it becomes necessary.

In Fig. 3, there is shown a modified form of cutter to indicate that various types of cutters may be employed and that the invention does not contemplate the use of any specific cutter except as defined by the appended claims. Cutters 23' are tapered and have the ordinary gears 24' making the use of angularly arranged cutters and track gear unnecessary. The rest of the parts are the same as shown by Fig. 1 and the invention operates in the same way.

It will of course be understood that the

pitch of the helical rib 4 and the helical groove 2 and the diameters of the gears will be such as to produce the desired revolving and rotating of the cutters. Particular attention is directed to the motion multiplying mechanism, comprising the annular gear 20 and the gears 17, 18, and 19 so that the required number of turns of the cutters is brought about by the predetermined longitudinal movement of the mechanism through the engagement of the gears as hereinbefore described.

For the sake of clearness, certain mechanical features have been deleted from the disclosure. For instance, it will be obvious that in order to reduce friction, ball bearings will be employed and any skilled mechanic will provide such bearings and other friction reducing means whenever it is found expedient to do so. The disclosure is such as to enable any person skilled in the art to make, construct and use the invention, but it should be understood that the disclosure is not intended to limit the invention to any particular form but the same may be embodied in other ways and changes in the form and construction may be made within the scope of the appended claims.

Having now described my invention, what I desire to claim and secure by Letters Patent of the United States is:

1. A pencil sharpener comprising rotating and revolving cutters, means for revolving said cutters and means for rotating said cutters operative upon a longitudinal movement thereof.

2. A pencil sharpener comprising revolving and rotating cutters and longitudinally movable means for operating said cutters including speed-multiplying means.

3. A pencil sharpener comprising revolving and rotating cutters mounted in a longitudinally and rotatably movable member and means for operating said cutters by said last mentioned member.

4. A pencil sharpener embodying a stationary inverted cup-shaped member, a movable member normally near the top of said cup shaped member, cutters associated with said movable member, elongated lugs depending from the top of said stationary member, and helical springs associated with said lugs and with said movable member.

5. A pencil sharpener embodying a stationary cylindrical member having a helical groove, a movable member having a rib co-operating with said helical groove to cause rotation of said movable member upon a longitudinal movement thereof, cutters associated with said movable member and longitudinally movable therewith and gearing between said movable member and said cutters whereby the rotation of said movable member causes rotation of said cutters.

6. A pencil sharpener embodying a hollow

- cylindrical member having a helical groove, a hollow cylindrical member having a rib cooperating with said helical groove to cause rotation of said last mentioned cylindrical member upon a longitudinal movement thereof and having an annular internal gear, cutters associated with said last mentioned cylindrical member and gearing associated with said annular gear for operating said cutters.
7. A pencil sharpener embodying a stationary cylindrical member having a helical groove, a movable cylindrical member having a rib cooperating with said helical groove to cause rotation of said movable member upon a longitudinal movement thereof, cutters associated with said movable member and rotatably movable with relation thereto and motion multiplying means between said movable member and said cutters.
8. In a pencil sharpener, a planetary cutter, a longitudinally movable support therefor; and means for operating said planetary cutter operative upon movement of said support.
9. In a pencil sharpener, a planetary cutter, a movable support therefor, spring means resiliently holding said support from movement, and means for operating said planetary cutter operative upon movement of said support.
10. In a pencil sharpener, a planetary cutter, a movable support therefor, means for operating said planetary cutter operative upon movement of said support, means responsive to pressure exerted on the pencil for moving said support in one direction and spring means for moving said support in the opposite direction.
11. In a pencil sharpener, a planetary cutter, a movable support therefor, means for moving said support, and motion multiplying means between the means for moving the movable support and said movable support.
12. A pencil sharpener comprising a planetary cutter, a movable support therefor, means responsive to pressure imparted to the pencil for moving said support, means operative upon movement of said support for operating said cutter, and means resiliently resisting contact of the pencil with the cutter before the operation of the cutter.
13. A pencil sharpener comprising a stationary member, a movable member, a planetary cutter associated with said movable member operative upon movement thereof, and spring means between said stationary and movable members.
14. A pencil sharpener comprising a stationary member, a longitudinally movable member, a planetary cutter associated with said longitudinally movable member and operative upon movement thereof, and spring means between said stationary and longitudinally movable members.
15. In a pencil sharpener of the character described, a pair of sharpening elements engaging the pencil point on opposite sides, means for reciprocating them and means for simultaneously rotating them around the pencil point.
16. A pencil sharpener comprising a casing, a frame mounted therein and spring supported in a raised position, a cutter supporting base carried by the frame, means for imparting revoluble movement to the base upon downward movement of the frame, diverging cutters on the revoluble base to rotate therewith, and means to impart revoluble movement to the cutters themselves as the frame is depressed.
17. In a pencil sharpener, a casing provided with a tubular guide, a base operatively connecting with the tubular guide to impart movement to the base upon downward movement of the latter, a spring supported frame in the casing and revolubly carrying the base, and revoluble cutters diverging upwardly from the base, and means to impart revoluble movement to the cutters themselves as they swing around the end of the pencil upon downward movement of the frame.
- In testimony whereof I affix my signature.
